UNITED STATES PATENT OFFICE.

EDWARD J. LEAMY, OF SYRACUSE, NEW YORK.

REVOLVING DOUBLE TRAPEZE.

SPECIFICATION forming part of Letters Patent No. 300,487, dated June 17, 1884.

Application filed December 3, 1883. (No model.)

To all whom it may concern:

Be it known that I, EDWARD J. LEAMY, of Syracuse, in the county of Onondaga and State of New York, have invented a new and Improved Revolving Double Trapeze, of which the following is a full, clear, and exact description.

The object of my invention is to provide a new and improved double trapeze adapted to be revolved on its transverse central axis.

The invention consists in a centrally-pivoted frame provided with means on one of the pivots for revolving the frame, from each end of which frame a trapeze is suspended.

The invention also consists in parts of construction, and details and combinations of the same, as will be fully set forth hereinafter.

Reference is to be had to the accompanying drawings, forming part of this specification, in which similar letters of reference indicate corresponding parts in both the figures.

Figure 1 is a perspective view of my improved revolving double trapeze. Fig. 2 is a longitudinal sectional elevation of the journal-box containing the mechanism for revolving the trapeze-frame.

Two trussed frames or side bars, A, have their ends united by transverse bars B, forming a quadrilateral frame. Each side bar is provided at its middle with an outwardly-projecting pivot, C, which pivots are journaled in the lower ends of the shanks of an inverted-U-shaped frame, F. One of the shanks of the frame F is provided at its lower end with an eye, a, or with an ordinary bearing, and to the lower end of the other shank a casing, D, is secured, in which the corresponding pivot, C, is journaled. A worm-wheel, E, contained within the casing D, is mounted on the corresponding pivot, C, and engages with a worm, G, secured on a vertical shaft, G', mounted in the casing D, from which shaft G' a rod, H, extends upward parallel with the corresponding shank of the frame F. The frame F is suspended from wires or cables J, secured to its cross-piece and passed through the ceiling K, and the said frame is braced by means of wires or cables L, secured to the upper and lower ends of the shanks of the frame. The upper

end of the rod H also projects through the ceiling K, and is provided at its upper end with means for turning it either by hand or

by machinery. On each cross-bar B two rings, M, are held to turn between suitable collars or annular ridges, which rings are provided with eyes or loops b, in which the upper ends of the ropes of a trapeze, N, are fastened.

In place of pivoting the quadrilateral frame in the ends of the shanks of the U-shaped frame F, the said frame can be pivoted in an upright frame or on standards; but in all cases one of the pivots is to be provided with means for turning the frame.

The apparatus is operated in the following manner: Each trapeze is mounted by a performer, and the quadrilateral frame is revolved slowly on its central transverse axis by turning the shaft H, whereby the worm G will be turned and will turn the wheel E and the pivot C, on which the said wheel is mounted. The trapezes at all times hang vertically from the cross-bars B, and the performers can perform on the trapeze in the same manner as on a stationary trapeze, the feats performed being of a somewhat different nature, as the trapeze-supporting frame revolves. The audience does not see the mechanism for revolving the trapeze-frame, as it is concealed by the casing D. If but one performer is to perform on the trapeze-frame, one end of the frame can be balanced in some suitable manner.

The trapeze can be of any desired shape, style, or construction.

Having thus described my invention, I claim as new and desire to secure by Letters Patent—

1. The combination, with a frame adapted to revolve in the vertical plane, of trapezes suspended from the said frame, substantially as herein shown and described.

2. The combination, with a revolving frame, of trapezes suspended from the same, substantially as herein shown and described.

3. The combination, with a centrally-pivoted frame, of means for revolving the same, and of trapezes suspended from the said frame, substantially as herein shown and described.

4. The combination, with a revolving frame, of means for revolving the same, contained in one of the journal-boxes, and of trapezes suspended from the said frame, substantially as herein shown and described.

5. The combination, with a revolving frame, of a worm-wheel mounted on one of the pivots, a worm engaging with the worm-wheel, a rod

for turning the worm, and a casing surrounding the worm-wheel and worm, in which casing the said pivot is journaled, substantially as herein shown and described.

5 6. The combination, with the side bars, A, provided at the middle with outwardly-projecting pivots C, of the cross-bars B, the worm-wheel E, mounted on one of the pivots C, the worm G, engaging with the worm-wheel, the

10 casing D, and the frame F, substantially as herein shown and described.

7. The combination, with the side frames, A,

each having a central pivot, C, of the cross-bars B, the worm-wheel E, mounted on one of the pivots, the worm G, engaging with the 15 worm-wheel, the frame F, and the rod H, extending upwardly from the worm G, parallel with and adjoining the corresponding shank of the frame F, substantially as herein shown and described.

EDWARD J. LEAMY.
